UNITED STATES PATENT OFFICE.

WALTER L. SIEWERS, OF WINSTON-SALEM, NORTH CAROLINA.

DESIGN FOR AN UNDERGARMENT.

43,786.

Specification for Design.

Patented Apr. 1, 1913.

Application filed December 7, 1912. Serial No. 735,536. Term of patent 14 years.

To all whom it may concern:

Be it known that I, WALTER L. SIEWERS, a citizen of the United States, residing at Winston-Salem, in the county of Forsyth and State of North Carolina, have invented a new, original, and ornamental Design for an Undergarment, of which the following is a specification, reference being had to the accompanying drawing, forming a part thereof.

The drawing is a perspective view of the garment seen from the front.

The garment shown in the accompanying drawing is composed of a tubular knit fabric 1 having the wales of the knitting running longitudinally of the garment with cuts 2 formed from opposite sides upon the curves shown and with V-shaped cuts

3 and 4 in the front and back respectively, such V-shaped cuts being of substantially equal depth and extending lower than the side cuts 2. The cuts 2, 3 and 4 are finished by an ornamental binding or beading 5, the beading from such cuts 2, 3 and 4 extending upwardly above the fabric and joined together as at 6 to form in their joined condition shoulder straps composed entirely of the ornamental beading.

I claim—

The ornamental design for an undergarment as shown and described.

WALTER L. SIEWERS.
